PROCESS OF DEHYDRATING MEATS CONTAINING FATS IN A FLUID CURRENT

William Alexander Noel, Washington, D. C., assignor to the United States of America, as represented by the Secretary of Agriculture

Application October 12, 1943, Serial No. 505,939

1 Claim. (Cl. 34—10)

(Granted under the act of March 3, 1883, as amended April 30, 1928; 370 O. G. 757)

1

This application is made under the act of March 3, 1883, as amended by the act of April 30, 1928, and the invention herein described, if patented, may be manufactured and used by or for the Government of the United States of America for governmental purposes without the payment to me of any royalty thereon.

This invention relates to a method of processing materials and apparatus therefor, with particular reference to the dehydration of ground meats containing fats using a flow of drying gas, such as heated air, for the dehydration.

According to conventional methods, granular materials to be dehydrated are loaded on trays and placed in a stream of drying gas. Other methods involve the use of revolving drums, and so forth, in which the materials being treated are agitated. These methods require the use of elaborate equipment and considerable attendance during operation.

In the dehydration, the materials being processed frequently are in contact with metal parts, such as tray floors, which are also subjected to the heated drying gas. This results in the metal parts being heated substantially to the dry bulb temperature of the drying gas, which ordinarily is considerably above the wet bulb temperature. In consequence, the dry bulb temperature must be held sufficiently low to prevent scorching of the material at the points of contact with the metal parts. This limit on the permissible dry bulb temperature limits the rate of dehydration.

The rate of dehydration is also limited due to non-uniformity of contact of the processing gas with all surfaces of the grains of the material, and in addition, the products are not uniformly treated. Furthermore, the time required in loading the trays into a tray-type dehydrator considerably reduces the overall capacity of such apparatus.

This invention has among its objects a method of dehydrating meats containing fats and removing the fats from the meats, and an apparatus which requires little attendance in use, which is simple in construction, using but few movable parts, which treats all grains of the meats uniformly, and which treats such material at a maximum rate, and such other objects as are apparent from the following description and claim.

In general, according to this invention, the meat in granular form is subjected to a stream of drying gas in such manner that the individual particles are separated from each other and suspended within the gas stream substantially out of contact with heated parts of the apparatus, and are conveyed through the treating apparatus by the flow of the gas. This is accomplished, in the embodiments of the apparatus herein described, by feeding the granulated meat into an

upwardly flaring tube, near its lower end while passing a stream of drying gas upwardly through the tube, in contact with the material, at such velocity that it carries the material upwardly, the grains of the material being suspended within the stream of gas during drying, following which they are delivered out at the top of the tube with the flow of drying gas and are then separated from it. At its lower end, the tube 10 communicates with a plenum chamber and the fats separate from the meat during the drying and drain into the plenum chamber from which they are separately collected.

For a detailed explanation of the invention, reference is made to the following description of the apparatus shown in the accompanying drawings, in which

Figure 1 is a side elevation showing two units of the apparatus, it being understood that any desired number of units may be used, all associated in the manner illustrated for the two, certain parts being broken away for clearness in illustration;

Figure 2 is a top view of the apparatus as shown in Figure 1, except enlarged and omitting the unit shown at the left of Figure 1;

Figure 3 is a view on line 3—3 of Figure 1, with parts broken away;

Figure 4 is a section on line 4—4 of Figure 1;

Figure 5 is a section on line 5—5 of Figure 3; and

Figure 6 is a diagrammatic illustration of a different arrangement of the units.

The granular meat to be dehydrated is fed from a hopper 11 into a screw conveyor 12 driven by a chain 13 and a suitable speed-reducing transmission 14 having a pulley 15 to be belted on a motor pulley. This provides means for feeding the material into a Venturi tube 16 through a suitable aperture in its wall. Drying gas flows through the Venturi tube and carries the material upwardly into the upright processing tube 17, which flares upwardly, resulting in a lowering of the velocity of the gas as it moves toward the upper end of the tube.

Assume a constant, properly regulated velocity of a drying gas entering the processing chamber and a moisture containing granular material to be dehydrated. The material is carried upwardly a fractional distance within the processing tube until it reaches a region where the air force tending to move it upwardly is in equilibrium with the force of gravity tending to move it downwardly. The grains of material are suspended within this region, and are continuously tumbled about, being first bounced upwardly beyond the level of equilibrium due to their momentum, and then falling somewhat below the level, repeatedly. As a result, the grains are dried uniformly on all surfaces. As the material dries it is usually so

altered that it is carried upwardly against the force of gravity more easily by a constant velocity of the processing gas. This may be due to change in its specific gravity, in the dimensions of the grains, in the surface resistance to flow of gas, or to a combination of these changes. Therefore, the material moves upwardly in the processing tube as it is being dehydrated until finally it is delivered out at the top through exit conduit 18. Regulation of the velocity of the gas with other factors constant determines the time that the material is dried.

The dried material and drying gas then pass tangentially into a cyclone collector 20 for separating the processed material from the gas. The collector has a cylindrical wall 21 merging into a funnel-shaped bottom 22. As the gas and material whirl about in the collector, the material falls into the funnel-shaped bottom, passing around the edge of a centrally disposed baffle 23 located beneath the open end of gas exit tube 24. The material is delivered from the collector through delivery conduit 25, either to the outside, if desired, or to further processing units, as later will be explained.

From gas exit tube 24 the drying gas passes into conduit 26, through heater 27, through conduit 28, into blower 29, which is preferably powered with a variable speed motor 30 and arranged to have variable speed belting coupling with the blower as by stepped pulleys 31 and 32, and from the blower through plenum chamber 33, returning to Venturi tube 16, the plenum chamber being in communication with the Venturi tube at the lower end of the tube.

The heater, which may be of any desired type, is here shown as a steam radiator 35 having an outlet pipe 36, and a steam inlet pipe 37 equipped with an air-operated valve 38 regulated by a thermostat 39, placed in the plenum chamber. Compressed air is supplied through a tube 40 connected between the thermostat and the valve and air supply tube 41 connected to the thermostat in a known manner. This provides for automatic regulation of the dry bulb temperature of the gas.

The wet bulb temperature is regulated by admitting outside dry air through port 42 controlled by damper valve 43 linked to the damper motor 44, which in turn is automatically controlled in a known manner by a hygrostat 45 also placed in the plenum chamber and connected to the damper motor by a tube 46 and to the supply tube 47.

Excess air is exhausted through port 48 controlled by a damper valve 49 manually set by operating rod 50.

Due to the location of ports 42 and 48 on opposite sides of the radiator 35, only the port 42 need be closely regulated to provide the desired wet bulb temperature. The radiator creates sufficient resistance to the flow of air so that, upon opening the valve 43, air enters at this point, and any approximate opening of port 48 which will allow escape of the replaced air is sufficient.

Adjustment of the air flow other than by varying the blower speed is provided by shut-off valves 51 and 52 located in conduit 28 and between the plenum chamber 33 and Venturi tube 16, respectively.

If it be desired to treat the materials with other gases, such as sulphur dioxide or flue gases, these may be admitted through port 42. In case waste hot flue gases are available, these may be used for drying without use of the heater, the

gases being exhausted to the outside after passing through the processing chamber and collector.

If blanching is desired, a blanching steam admission pipe 55 communicating with the processing tube 17 near its lower end may be used. Also, pipe 55 may be employed to admit steam in case the processing gas is too dry.

A hot water or steam admission pipe 56 may be additionally provided for cleaning purposes. 10 All that is necessary to clean and sterilize the apparatus is to turn in steam or hot water and circulate the hot air until the parts are thoroughly clean and sterile. The resulting wash water runs down the processing tube into the plenum chamber, from which it is readily drained.

The description thus far relates to but one unit. Such a unit may be used by itself either in a continuous process, as described above, or 20 in a batch process. In the latter case (which may be necessary if the nature of the material being processed is such that it is not altered sufficiently while being treated to cause it to be carried over with the processing gas, as, for 25 example, in case of cooking meat at 100 percent relative humidity), a batch is loaded into the processing tube and after a desired interval of treatment, while suspended in the tube, the gas velocity is increased to blow the batch over into the cyclone collector.

By the batch method, if there is some degree of alteration, as is usually the case, it is also possible to separate fractions of the material which are altered the more rapidly from the other 35 fractions, since they can be passed into the collector before materials which are altered the less rapidly. In case of dehydration of ground meats of non-uniform sizes of the particles, for example, the smaller particles collect first.

40 Also, with a single unit the same materials may be given separate processing steps in the batch method. For example, a batch of the granular material may be introduced into the processing tube, be given a first treatment with sulphur dioxide gas, a second treatment with blanching steam, and successive treatments with dehydrating gas at varying relative humidities and temperatures. Finally, the treated materials may be fractionated as above explained.

50 In dehydration in this apparatus of meats, liquids, such as fats, separate from the meats, and drain into the plenum chamber. In order to collect and remove them, the plenum chamber is arranged on a decline, in the manner illustrated 55 in Figure 1. The liquid materials flow toward the left-hand end of the chamber and are drained therefrom through a conventional U-tube trap 60 which is of sufficient length to prevent blowing the processing gas out through the U-tube. Thence, the liquids may be collected or returned to the dehydrated materials, as desired.

In case of cleaning the apparatus, the wash water is also drained out through the U-tube trap, or through a suitable gate 61, as shown at 65 the left-hand end of the plenum chamber in Figure 1.

The Venturi tube 16 is provided to form a suction inlet at the point of admission of material from the conveyor 12, and also provides a 70 means of increasing the velocity of the gas at this point. It is not necessary to provide a Venturi tube in all instances. For example, by terminating the screw of the conveyor short of the exit end of its enclosing pipe in a manner 75 illustrated in Figure 1, with many materials a

packing effect is obtained at the exit end of the pipe which prevents blowing of the processing gas back through the conveyor. However, it is desirable to provide a restricted passage for the gas at this point in order to obtain a gas velocity sufficient to carry the material introduced therein upwardly into the processing chamber.

Any number of supplemental units may be employed, depending on the capacity desired. One such supplemental unit is illustrated in Figure 1, and is similar to the unit above described, similar parts being given similar characters except primed. As shown, the supplementary unit is arranged in such manner to use the same blower and heater, being connected in parallel with the other unit in the gas-circulating system. However, the materials pass through the various units in series, according to the particular embodiment illustrated. Thus, the material processed by the first unit feeds from the bottom 22 of the first collector into the tube 25 and into the Venturi tube 16 of the second unit. By adding units in this manner, increased capacity is obtained, since the materials can thereby be given a partial treatment in each unit and then be passed on to the next unit for more complete treatment.

Gravity feed may be used for conveying the materials from one unit to the next unit if the collectors are elevated, or any other suitable type of conveyor may be employed. In case the Venturi tube is omitted, a one-way feeding valve 65 is installed in tube 25. Valves suitable for this purpose are known. The one shown comprises a set of radial fins 66 fittingly rotatable in a casing 67 and driven in any convenient manner. The fins block off back passage of gas, but as they rotate material is dumped at the upper inlet of the casing into the pockets between the fins and is dumped out of the pockets at the lower outlet of the casing. Stopping rotation of the fins stops feeding.

If the last unit be employed to separate the materials fractionally, which is accomplished in the batch process, the prior unit may nevertheless be operated continuously, since the material may be allowed to collect in its collector and then be fed as a batch into the succeeding processing chamber.

In case of dehydrating, the successive units may be of decreasing size, as shown, since the volume of the material ordinarily decreases as it is dehydrated.

Although the apparatus shown uses but one blower and heater and but one set of controls, in some instances it may be desirable to employ a separate blower, heater and controls for each unit with the materials passing in series through the several units. With such arrangement, several different treatments may be given the materials in a continuous process. For example, the materials may be gassed with sulphur dioxide in the first unit, blanched in the second unit, and dehydrated with varying temperatures and humidities in the other units, and a cooking or roasting unit may be added.

Such an arrangement is illustrated in Figure 6 showing two units, the first of which is provided with a processing chamber 80, collector 81, heater 82, blower 83, and plenum chamber 84, and the second with corresponding parts having the same reference characters except primed. The collector from the first unit is connected to feed into

the processing chamber of the second unit. Details of the several units are similar to details heretofore described in reference to Figures 1-5.

The parts of the apparatus may be constructed from any suitable material, stainless steel or enameled iron being preferable from the standpoint of cleanliness. As shown, opposite walls of the processing tubes are provided with inspection windows 10 in order to observe the materials therein. However, a more desirable construction would be the use of a transparent material for at least two opposite walls.

As an example of the method using a single unit with this type of apparatus having a processing chamber 11 inches by 11 inches at the bottom, 12 inches by 18 inches at the top, and about 18 feet high, 32 pounds of cooked granulated pork with a moisture content of 54 percent was fed into the processing chamber in a batch while passing processing air through the chamber at 200° F., dry bulb, and 155° F., wet bulb, at the rate of about 1800 cubic feet per minute. The temperature of the air first fell to about 170° F., but rose to about 200° F. in about 15 minutes. Within about 20 minutes from the time of loading the batch into the processing chamber, the very finely divided particles of dehydrated meats started passing into the collector, and the largest particles passed into it in about 45 minutes. On test the dehydrated meat showed a moisture content of about 7 percent.

The conditions indicated above are not optimum, and better results are obtained by using a higher wet bulb temperature, and by avoiding the initial drop in temperature possible if pre-heated materials are fed into the apparatus and a large capacity heater is used.

Many other tests using the apparatus with various other types of materials showed excellent results both as to ease of attending the apparatus and as to the rapidity and uniformity of the processing.

With light materials (the specific gravity of which is well below one), the process of dehydrating is especially applicable, since these materials change their factors, especially decreasing their density with the loss of water, more rapidly than do heavier materials, with the result that they are conveyed more readily upwardly in the processing chamber during the processing operation.

Having thus described the invention, what is claimed is:

A method of dehydrating meats containing fats, comprising introducing granulated meat at a low region into an upwardly flaring tube having a plenum chamber communicating with the tube at its lower end, said tube having passing therethrough an upwardly flowing stream of heated, drying gas at such velocity as to carry the granulated meat upwardly in the tube whereby, due to decrease of velocity of the gas as it flows upwardly in the tube, the grains of meat are gradually conveyed upwardly during drying from one region to a higher region where the gas force tending to move them upwardly is in equilibrium with the force of gravity tending to move them downwardly and whereby the fats separate from the meat and drain into the plenum chamber, and separately collecting the fats from the plenum chamber and the dehydrated meat from the tube.

WILLIAM ALEXANDER NOEL.
